CLAIM

The ornamental design for an electric vacuum cleaner body, as shown and described.

DESCRIPTION

FIG. 1 is a front, left and top perspective view of an electric vacuum cleaner body showing our new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the electric vacuum cleaner body in accordance with our new design illustrating a state in which an environmental structure (a nozzle) is attached to the electric vacuum cleaner body. The dust collection capsule of the electric vacuum cleaner body in accordance with our new design is transparent or translucent.

The broken lines in the drawings illustrate the environmental structure or portions of the electric vacuum cleaner body which form no part of the claimed design.
